LIFEBOAT SYSTEM

Stafford W. Trexler and Earl A. Belt, Baltimore, Md., assignors of twenty-five percent to James E. Stansbury, Annapolis, Md.

Filed Nov. 30, 1964, Ser. No. 414,576

8 Claims. (Cl. 9—39)

This invention relates generally to improvements in life boats, and more particularly it pertains to a supporting and handling system for lifeboats.

One of the objects of this invention is to provide a boat of this character which is safe and comfortable and incorporates a completely covered hull structure whereby the occupants of the boat are protected from the elements and swamping of the boat by high waves is prevented.

Another object of this invention is to provide improved supporting system which cradles the boat securely against movement in the stowed position and holds it securely while being loaded.

Still another object of this invention is to provide a lifeboat lowering mechanism which is entirely controlled by the occupants of an enclosed capsule-type lifeboat thereon supported.

Other objects and attendant advantages of this invention become more readily apparent and understood from the following detailed specification and accompanying drawings in which:

FIG. 1 is a side elevation of a lifeboat system incorporating features of this invention;

FIG. 2 is a plan view thereof, partly broken away;

FIG. 3 is an end elevation of the life boat system of FIG. 1, partly broken away and showing the stowed position of the capsule;

FIG. 4 is a view similar to FIG. 3 but showing the capsule lowering position of the davits; and

FIG. 5 is an enlarged vertical section taken on line 5—5 of FIG. 3 depicting details of a lowering cable release mechanism.

Referring now to the details of the drawings in FIGS. 1 to 5, reference numeral 10 indicates generally a vessel having a deck 12 and a deckhouse 14 thereon. A pair of spaced davits 16 are provided which rise from the deck 12. These davits 16 are each formed with an arced supporting portion 18 and an upwardly extended rear portion 20.

The concave surface 22 of the davits 16 is lined with a plurality of buffers 24, which may be of rubber or stuffed canvas or the like.

Pivot pins 26 attach the davits 16 to brackets 28, which, in turn, are secured to the deck 12. A support 30 is mounted on top of the deckhouse 14 opposite to each davit 16 and this support has a sheave 34 upon an extending bracket 32. A stop 36 for contacting a davit 16 in stowed position also extends from each bracket 30 and carries a cushion 38 on its contacting face.

In the launching position, the davits 16 as best shown in FIG. 4 rest upon a similar cushion 42 of a support 40 mounted on the deck 12.

A twin cable winch 44 is secured on the deck intermediate the davits 16. This winch 44 is of the free run-off type and is provided with a weighted brake arm 46 which sets the winch brake 48.

A pair of cables 50, 52 lead from the winch 44 to a double fairlead 54, 56, which respectively direct the cable 50 toward the forward davit and the cable 52 toward the aft davit.

Enroute, a pair of sheaves 58 on the deckhouse wall change the direction of the cables 50, 52 so as to pass them over the previously mentioned bracket sheaves 34 near the tops of the supports 30 upon the deckhouse.

2

From there the cable 50, 52, extend to sheaves 60 on the extended portions 20 of the davits 16 and thence are routed about sheaves 62, 64, 66 and 68 spaced along one side of each davit.

From the last sheave 68, upon the tip of the arced portion 18, the cables 50, and 52 depend to each pass around a pulley 70, reversing direction to again return to the tip of the portions 18, around sheaves 72, 74, 76, 78 and 80 spaced upon the other sides of the davits. The ends 10 of the cables 50, 52 terminate in swiveled turnbuckles 82 which are attached to fittings 84 on the supports 30.

A loading platform 86 of grilwork or expanded metal extends on supports 88 built out from the overhead of the deckhouse 14 and has an access ladder or stair 90. 15 A guard rail 92 extends around the platform and sides of the stairs for safety to personnel as they are loaded into a capsule 94.

This capsule 94 is supported fore and aft by the pulleys 70 each of which initially nest in a cavity 96 thereof. As 20 best shown in FIG. 5, the pulley housing 98 of each pulley 70 is provided with a reduced neck 100 which has a ball 102 formed on its end.

This ball 102 is captivated in a hollow capsule release fitting 104 which is mounted for rotation on a stub 25 shaft 106 journaled in the side of the cavity 96. The captivating slot 108 in the fitting 104 terminates in a ball release aperture 110 normally at the side but which can be rotated upwardly when the fitting 104 is turned by a release lever 112 inside the capsule on the end of shaft 106.

The capsule 94 is a watertight floatable hull with an observation dome 114 over-all. Reference numerals 116 indicate the access doors in its sides. A stabilizing or ballast section 118 is provided in the capsule low down 35 in the hull. Battery and provision storage sections 120 and 122 are provided as well as a radio 124 and the remaining space 126 is a passenger compartment.

Stabilizer fins 128 are mounted on the outside of the hull and the craft is arranged with a motor 130, a propeller 136 and a rudder 138 for propulsion and guidance of the craft. A transmission 132 is provided to disconnect the motor 130 from the propeller drive shaft 134 and connect the latter to a manual drive shaft 142 when a lever 140 is operated.

45 The shaft 142 extends lengthwise inside the capsule and at spaced intervals has bevel gears 144 and hand cranks 146 enabling the passengers to propel by hand if desired.

The launching of the capsule is by gravity. The overhang of the capsule 94 with respect to the pivot 26 of the davit causes a tension at all times on the cables 50, 52. This is held by the weighted winch brake arm 46 until a release cable 148 attached thereto is tensioned. The cable 148 leads around a fairlead 150 on the davit 55 16 and thence through an aperture (not shown) into the interior of the capsule. An occupant of the capsule can thus cause the winch brake 48 to release at will allowing the cables 50, 52 to pay out freely from the winch 44. The davits 16 first swing out from the position shown in FIG. 3 to that shown in FIG. 4. Then the davits rest 60 and as more cable is paid out the capsule 94 lowers to the water level.

When the levers 112 of the release mechanism 104, 106 are rotated the ball 102 of each pulley neck 100 is released and the capsule 94 is freed.

To prevent the capsule 94 from swinging away from the buffers 24 in the case of heavy seas and severe rolling of the parent vessel 10, a pair of lines or gripes 204 are provided from attachment points 206 on each extremity 70 of the supporting portion 18 of the davits. These gripes 204, as best shown in FIG. 3, pass halfway around the outer side of the capsule 94, over a post 208 fixed part

way up on the davit 16 and thence terminate in a tie down device 210 such as a cleat stile lower down.

Still another safety feature lies in the provision of a stowage hook 200 which extends outwardly from the support 18 just below the sheave 68 and captures a loop 202 of the pulley housing 98 as long as the davits 16 are vertical as shown in FIGS. 3 and 5. When the davits 16 are lowered as previously described, the hook 200 automatically disengages from the loop 202 to free the capsule 94 for lowering to the water.

Obviously many modifications and variations of the present invention are possible in light of the above teachings. It is, therefore, to be understood that within the scope of the appended claims the invention may be practiced otherwise than as specifically described.

What is claimed is:

1. In a vessel having a deck and a deckhouse, a pair of spaced davit members pivotally mounted at their lower ends to said deck, each said davit members having a portion upwardly extending from the rear portion thereof and an arc portion outwardly facing from the front thereof, stop means for defining the stowed and launching positions of said davit members, a lifeboat, means for stowing said lifeboat against the arc portion of each said davit members and lowering it therefrom, including a pair of cables releasably engaged with said lifeboat, a plurality of sheave elements positioned along each side of said arc portion and said upwardly extending rear portion, with the sheave elements along one side of each said arc portion being for guiding its corresponding cable to said lifeboat and the sheave elements along the opposite side of each said arc portion being for guiding its respective cable away from said lifeboat, a pair of additional sheave elements positioned along said deckhouse for guiding one end of each said cables therewith, a winch mechanism mounted on said deck for receiving said one end of each said cables to obtain manipulation thereof, and means securing the opposite end of each said cables to said deckhouse.

2. In a vessel having a deck and a deckhouse, a pair of spaced davit members pivotally mounted at their lower ends to said deck, each said davit members having an upwardly extending rear portion and outwardly facing arc portion, stop means for defining the stowed and launching positions of said davit members, a lifeboat having a propulsion element, a motor mechanism for driving said propulsion element, manually operated means for driving said propulsion element, and clutch means for disconnecting said motor mechanism from said propulsion element upon operation of said manually operated means, means for stowing said lifeboat against the arc portion of each said davit members and lowering it therefrom, including cables releasably engaged with said lifeboat, sheave elements for guiding said cables along each said arc portion, each said upwardly extending rear portion, and deckhouse, and a winch mechanism mounted on said deck for receiving said cables to obtain manipulation thereof.

3. In the vessel as recited in claim 2 wherein said lifeboat is a water-tight enclosed capsule.

4. In the vessel as recited in claim 3 wherein said capsule has an observation dome.

5. In a vessel having a lifeboat and davit structure including a pair of cables for suspending said lifeboat, means for releasably engaging said cables with said lifeboat, comprising a pulley retained by each of said cables, each said pulley having a yoke with an enlarged element, a housing corresponding to each said pulley rotatably mounted to said lifeboat and having a slot for captivating said enlarged element within said housing, with said slot terminating in an aperture for releasing said enlarged element from said slot upon rotation of said housing to thereby release said lifeboat from each said cables.
- 10 15. 6. In the vessel as recited in claim 5 and additionally, a shaft element for rotating said housing by an occupant of said lifeboat.
- 20 7. A lifeboat comprising structure defining a water-tight, floatable, enclosed capsule, an element for propelling said capsule, a motor mechanism for driving said element, manually operated means for driving said element, and transmission means for alternating connection of said motor mechanism and said manually operated means with said propelling element.
- 25 8. In a vessel having a deck and a deckhouse, a pair of spaced davit members pivotally mounted at their lower ends to said deck, each said davit members having an upwardly extending rear portion and outwardly facing arc portion, stop means for defining the stowed and launching positions of said davit members, a lifeboat, means for stowing said lifeboat against the arc portion of each said davit members and lowering it therefrom, including cables releasably engaged with said lifeboat, sheave elements for guiding said cables along each said 30 35 arc portion, each said upwardly extending rear portion, and deckhouse, and a winch mechanism mounted on said deck for receiving said cables to obtain manipulation thereof, the releasable engagement of said cables with said lifeboat being provided by each of said cables passing over a pulley, each said pulley having a yoke with a ball element positioned at one end thereof, a corresponding housing rotatably mounted to said lifeboat and having a slot for captivating said ball element and an aperture for releasing said ball element from said slot upon rotation of said housing to thereby release said lifeboat from said cables.
